LIQUID STORAGE CONTAINER AND LIQUID EJECTION APPARATUS

BACKGROUND

Field of the Disclosure

The present disclosure relates to a liquid storage container and a liquid ejection apparatus.

Description of the Related Art

There are inkjet-type printers (recording apparatus) that each include an ink tank capable of storing ink to be supplied to a recording head that ejects ink. Some recording apparatuses allow a user to inject ink into an ink tank from an injection port of the ink tank. On this type of these recording apparatus, it is desirable to take measures to prevent ink falling around the injection port from staining a surface of the ink tank which can be seen by the user. Japanese Patent No. 6554835 discusses a configuration of guiding ink, present on an injection port face, through a container guiding path from the injection port face in a direction different from the direction of a surface that can be seen by users, inhibiting the arrival of the ink at the surface.

In the configuration of Japanese Patent No. 6554835, however, the ink flowing in the container guiding path from near the injection port may escape to the outside of the ink tank due to a change in orientation of the recording apparatus or a shock from outside the recording apparatus.

SUMMARY

The present disclosure is directed to inhibiting escape of liquid to the outside of a liquid storage container.

According to an aspect of the present disclosure, a liquid storage container includes a storage portion configured to store liquid, an opening portion provided on a first surface and configured to allow injection of the liquid into the storage portion, a liquid receiving portion consisting of the first surface and a wall disposed around the opening portion on the first surface, and a liquid holding unit configured to hold the liquid guided by a guiding portion from the liquid receiving portion to outside of the liquid receiving portion. The liquid holding unit includes a second surface different from the first surface of the liquid storage container and a flexible member.

Further features of the present disclosure will become apparent from the following description of embodiments with reference to the attached drawings.

BRIEF DESCRIPTION OF THE DRAWINGS

FIG. 1 is a perspective view illustrating an outline of the internal configuration of a recording apparatus according to a first embodiment of the present disclosure.

FIG. 2 is a perspective view of an ink supply unit according to the first embodiment.

FIG. 3 is an external perspective view of the recording apparatus according to the first embodiment.

FIGS. 4A and 4B are exploded perspective views of an ink tank according to the first embodiment.

FIGS. 5A and 5B are side views of the ink tank according to the first embodiment.

FIGS. 6A to 6C are external perspective views of the ink tank according to the first embodiment.

FIG. 7 is a diagram illustrating an injection state where an injection bottle is attached to the ink tank according to the first embodiment.

FIGS. 8A to 8C are diagrams illustrating a procedure for attaching the injection bottle to the ink tank according to the first embodiment.

FIG. 9 is a YZ sectional view of the injection bottle and the ink tank with the injection bottle pulled from the ink tank according to the first embodiment.

FIG. 10 is an enlarged view of a part including a needle of the ink tank according to the first embodiment.

FIG. 11 is a schematic view of the ink tank according to the first embodiment, when viewed from a +X direction.

FIG. 12 is a perspective view illustrating an outline of a part including the ink tank disposed in a housing according to the first embodiment.

FIG. 13 is a sectional view of the ink tank according to the first embodiment, taken along a line B-B in FIG. 11, and viewed from a +Y direction.

FIG. 14 is a sectional view of the ink tank according to the first embodiment, taken along a line C-C in FIG. 11, and viewed from a +Z direction.

FIGS. 15A and 15B are external views of an ink tank according to a second embodiment.

FIG. 16 is an enlarged sectional view of a part including an ink channel of the ink tank according to the second embodiment, taken along a line D-D in FIG. 15B.

FIG. 17 is a top view of a part including the ink tank disposed in a housing according to the second embodiment, when viewed in a +Z direction.

DESCRIPTION OF THE EMBODIMENTS

Exemplary embodiments will be described in detail below with reference to the attached drawings. The following embodiments do not limit the present disclosure according to the scope of claims. While a plurality of characteristics is described in the embodiments, not all of these characteristics are necessarily used for the disclosure, and the characteristics may be freely combined. FIG. 1 is a perspective view illustrating an outline of an internal configuration of a recording apparatus (a recording apparatus 100) according to a first embodiment of the present disclosure. The recording apparatus 100 according to the present embodiment is an inkjet recording apparatus that performs recording on record media by ejecting ink, but the present disclosure is also applicable to various types of recording apparatus (liquid ejection apparatuses) other than the inkjet recording apparatus. In the drawings, arrows X and Y indicate directions intersecting each other, and in the present embodiment, these are orthogonal to each other. An arrow Z indicates the vertical direction (gravitational direction). The X directions are the width directions of the recording apparatus 100 (i.e., the left-right directions, or the width directions of the record medium). The Y directions are the depth directions (front-back directions) of the recording apparatus 100.

The term “recording” includes, in addition to cases where meaningful information, such as characters and graphics, are formed, a wide variety of cases where images, designs, patterns, and the like are formed on record media or the record media are processed, regardless of whether information is meaningful or meaningless, and it does not matter whether the result of recording is visualized to be perceivable by a human being. In addition, while sheet paper is used as “record medium” in the present embodiment, other materials, such as cloth and plastic film, may be used.

The recording apparatus 100 includes a sheet feeding unit 110, and a record medium placed on the sheet feeding unit 110 is fed by a feeding roller (not illustrated). The record medium fed by the feeding roller is inserted between a conveyance roller 1 and a pinch roller 2 that is driven by the conveyance roller 1, and conveyed in a +Y direction while being guided and supported on a platen 3 by the rotation of the conveyance roller 1. The conveyance roller 1 is a metal roller having minute irregularities in the surface processed to generate a large frictional force. The pinch roller 2 is elastically urged toward the conveyance roller 1 by a pressing member, such as a spring (not illustrated). The platen 3 supports the back surface of the record medium so that the distance between an ink ejection surface of a recording head 4 serving as a liquid ejection head and the opposite front surface of the record medium is held at a predetermined distance. Upon completion of recording by the recording head 4, the record medium conveyed onto the platen 3 is discharged toward the front (front surface) side of the recording apparatus 100 by a discharge roller and a driven roller that is a rotational body being driven by the discharge roller (neither roller illustrated). The discharge roller is a rubber roller having a large friction coefficient. The driven roller is elastically urged toward the discharge roller by a pressing member, such as a spring (not illustrated).

The recording head 4 is removably mounted on a carriage 7, in an orientation for ejecting ink toward the record medium. The carriage 7 is reciprocated by a driving unit, such as a motor, in the X directions along guide rails 5 and 6 disposed at an upper position and a lower position, respectively. The recording head 4 has a plurality of nozzle arrays to discharge the respective inks of different colors. An ink tank 8, which is each of a plurality of independent liquid storage containers corresponding to the colors of the inks to be discharged from the recording head 4, is disposed on the front side of the recording apparatus 100 in the +Y direction. The ink tanks 8 may be collectively disposed at a position on the rear side (back side) in the +Y direction, the right side in the +X direction, or the left side in the +X direction, of the recording apparatus 100. The ink tanks 8 and the recording head 4 are connected to a plurality of tubes 16 (see FIG. 2) each corresponding to a corresponding color of the colors of the respective inks via a joint (not illustrated). The ink stored in each of the ink tanks 8 is independently supplied through the tube 16 to the nozzle array corresponding to the color of the corresponding ink in the recording head 4.

FIG. 2 is a perspective view of an ink supply unit according to the present embodiment. As described above, the recording apparatus 100 includes the plurality of ink tanks 8, which are ink tanks 8BK, 8C, 8M, and 8Y according to the present embodiment. The ink tanks 8BK, 8C, 8M, and 8Y store inks of black, cyan, magenta, and yellow, respectively. The ink tank 8BK is disposed on the left side of the recording apparatus 100 in the +X direction, and the ink tanks 8C, 8M, and 8Y are disposed next to each other on the right side in the +X direction. The inks are not limited to four types as in the present embodiment, and ink of one type may be used, or inks of a plurality of types other than four may be used. It is suitable that the number of the ink tanks 8 is greater than or equal to the number of the types of ink. In the present embodiment, the ink tanks 8BK, 8C, 8M, and 8Y have similar configurations, and one of the ink tanks 8 will be described below as a representative in the description of the ink tank 8.

FIG. 3 is an external perspective view of the recording apparatus 100 according to the first embodiment of the present disclosure. The front surface, the back surface, and

the side surfaces of the internal configuration of the recording apparatus 100 illustrated in FIG. 1 are covered with a housing 200. The housing 200 has windows 201a to 201d that can be seen by users, and a user can look at a front portion 21b (see FIGS. 4A and 4B) of each of the ink tanks 8 from the corresponding one of the windows 201a to 201d. A needle 22 (see FIGS. 4A and 4B) that is a liquid injection portion of the ink tank 8 has an opening portion 220 (see FIGS. 5A and 5B) at its upper end, and the opening portion 220 is closed with the corresponding one of caps 202a to 202d for the respective ink tanks 8.

For a user to inject ink into the ink tank 8 as will be described below, turning the cap 202 corresponding to the ink tank 8 as an ink injection target allows the user to access the needle 22. The recording apparatus 100 includes a cover 210 for covering the upper part of the internal configuration illustrated in FIG. 1. By opening the cover 210, the user can access the cap 202 and inject the ink into the ink tank 8. According to the present embodiment, the needle 22 has the opening portion 220, but a form in which the ink tank 8 has a simple opening as the opening portion 220 may be used.

The structure of the ink tank 8 will be described with reference to FIGS. 4A and 4B and FIGS. 5A and 5B. FIGS. 4A and 4B are exploded perspective views of the ink tank 8C. FIGS. 5A and 5B are side views of the ink tank 8C. FIG. 5A illustrates a side surface 21d, and FIG. 5B illustrates a side surface 21c.

An outlet portion 26 in a cylindrical shape is formed in a rear part of the ink tank 8C. The outlet portion 26 is an outlet for the ink stored in the ink tank 8C, and is a liquid outflow port for the ink to flow out to the recording head 4. The tube 16 is connected to the outlet portion 26, and the ink stored in the ink tank 8C is supplied to the recording head 4 from the outlet portion 26 via the tube 16.

A lower limit display portion 24b for displaying an indication for the lower limit of the amount of ink for refilling of ink and an upper limit display portion 24a for displaying an indication for the upper limit in injecting ink are formed at the front portion 21b.

An engagement portion 23a is formed at the front portion 21b of the ink tank 8C, and an engagement portion 23b is formed at the rear portion. The engagement portions 23a and 23b each engage with an engagement portion (not illustrated) formed on the housing 200 of the recording apparatus 100, thereby fixing and positioning the ink tank 8C.

The ink tank 8C has a storage portion 25 for storing ink, on the bottom side. The storage portion 25 is defined by a space opened behind the side surface 21d of a main body 21 of the ink tank 8C, and a film 20b. The storage portion 25 communicates with the needle 22 via flow paths 31 and 32. The flow paths 31 and 32 are each defined by a groove opened at the side surface 21c (second side surface) of the main body 21, and a film 20a (flexible member).

The storage portion 25 and the outlet portion 26 communicate with each other via a flow path 29a. The flow path 29a is defined by a groove opened at the side surface 21c of the main body 21, and the film 20a. The ink stored in the storage portion 25 is supplied to the recording head 4 through the flow path 29a, the outlet portion 26, and the tube 16.

FIGS. 6A to 6C are external perspective views of the ink tanks 8C, 8M, and 8Y. FIG. 6A, FIG. 6B, and FIG. 6C are perspective views of the ink tanks 8C, 8M, and 8Y, and correspond to a view from the +Y direction, a view from the -X direction, and a view from the -Y direction, respectively. The ink tank 8 according to the present embodiment has an ink receiving portion 18b surrounding the needle 22 in four directions using a wall 18a, and an ink holding member 19

is disposed in the ink receiving portion **18b**. Two detection pins **14** (detection unit) for detecting the amount of ink in the storage portion **25** are disposed on the rear side opposite the front portion **21b** of the ink tank **8**. The detection pins **14** connect to an electric board **15**, and detect whether the amount of ink is a predetermined amount or more, based on the difference between the electrical resistance values of the respective detection pins **14**. The one electric board **15** is shared with the ink tanks **8C**, **8M**, and **8Y**, and is disposed on the side surfaces of the respective ink tanks **8** in the **-Y** direction. The wall **18a** of the ink receiving portion **18b** is not limited to a form surrounding the needle **22** in the four directions, and may be a U-shaped wall opened in one direction, or may have a shape opened in a predetermined direction, such as a dog-leg shape or a circular arc shape. The detection pins **14** and the electric board **15** are not limited to this configuration in terms of the position and the number thereof. The detection pins **14** may be three or more pins. The electric board **15** may be disposed for each of the ink tanks **8**, and each of the electric boards **15** may be connected to the detection pins **14**.

FIG. 7 is a diagram illustrating an injection state where an injection bottle **24** is attached to the ink tank **8C**. FIGS. **8A** to **8C** are diagrams illustrating a procedure for attaching the injection bottle **24** to the ink tank **8C**. The injection bottle **24** is a bottle storing ink to be injected into the ink tank **8**.

The injection bottle **24** is prepared for each type of ink, to inject the ink into the ink tank **8** of the corresponding ink. While the injection bottle **24** illustrated in FIG. 7 and FIGS. **8A** to **8C** is a bottle for cyan ink, an injection bottle corresponding to each of other types of ink has a similar structure.

The injection bottle **24** includes a storage portion **51** for storing ink, and a closing member **52** fixed to an end portion of the storage portion **51**. The storage portion **51** is a cylindrical container whose one end portion is open, and the closing member **52** is fixed to the storage portion **51** to close the open end portion.

An insertion hole **53** into which the needle **22** is to be inserted is formed in the closing member **52**. The insertion hole **53** communicates with the storage portion **51** via a valve **55**. A seal member **54** is disposed around the insertion hole **53**. The valve **55** includes an opening/closing member **55a** movably disposed, and a spring **55b** that urges the opening/closing member **55a** in the closing direction. The opening/closing member **55a** is urged by the spring **55b** to be brought into contact with the seal member **54**, thereby being positioned at the closed position for blocking the communication between the insertion hole **53** and the storage portion **51**.

Ink injection work using the injection bottle **24** will now be described. Here, a case of injecting the cyan ink into the ink tank **8C** will be described as an example. The user prepares the injection bottle **24** storing the cyan ink. In addition, the user removes the cap **202c** from the needle **22** of the ink tank **8C**. Subsequently, as illustrated in FIG. **8A**, the user attaches to the ink tank **8C** the injection bottle **24** in an orientation in which the closing member **52** faces downward so that the needle **22** can be inserted into the insertion hole **53**.

FIG. **8B** illustrates a state where the injection bottle **24** is pushed to the ink tank **8C**, and the needle **22** has started to be inserted into the insertion hole **53**. At the stage in FIG. **8B**, the needle **22** has not arrived at the opening/closing member **55a**, and the valve **55** remains in the closed state.

FIG. **8C** illustrates a stage where the attachment of the injection bottle **24** is completed. The needle **22** pushes up the

opening/closing member **55a** against the urging force of the spring **55b**, and the opening/closing member **55a** is shifted to the open position away from the seal member **54**. The valve **55** is in the open state, and the storage portion **51** and the flow paths **31** and **32** of the needle **22** are in the communicating state. The cyan ink in the storage portion **51** flows from one of the flow paths **31** and **32** into the ink tank **8C**, and air in the ink tank **8** flows into the injection bottle **24** through the other flow path. The air in the ink tank **8** and the liquid in the injection bottle **24** are thereby replaced with each other, so that the ink is injected into the ink tank **8**.

Upon completing the injection of the ink, the user removes the injection bottle **24** from the ink tank **8C**. The removal work is performed in the reverse procedure to the attachment. When the injection bottle **24** is raised from the state in FIG. **8C**, the needle **22** becomes away from the opening/closing member **55a**, and thus returns to the state in FIG. **8A**. The opening/closing member **55a** is returned to the closed position by urging of the spring **55b**, and the valve **55** returns to the closed state.

FIG. **9** is a YZ sectional view of the injection bottle **24** and the ink tank **8** in a state where the injection bottle **24** is pulled from the ink tank **8**. Upon completing the injection of the ink into the ink tank **8C**, the user pulls the injection bottle **24** from the needle **22**. At this moment, the ink can run down the outer side of the needle **22** to stain the outer surface of the ink tank **8**. The ink running down the outer side of the needle **22** flows in the gravitational direction (**-Z** direction), and toward the upper surface of the ink tank **8C**, as indicated by an arrow.

The ink that has arrived at the upper surface of the ink tank **8C** spreads on the XY plane, but remains in the ink receiving portion **18b** due to the wall **18a**, and a part of the ink is absorbed in the ink holding member **19** disposed in the ink receiving portion **18b**. The ink holding member **19** is made of a material capable of absorbing and holding liquid, such as a porous material, a foam material, or a fiber material. The ink running down near the needle **22** is held in the ink receiving portion **18b** with the wall **18a** and the ink holding member **19**.

FIG. **10** is an enlarged view of a part including the needle **22** of the ink tank **8C**. As described above, the ink running down near the needle **22** is held in the ink receiving portion **18b** with the wall **18a** and the ink holding member **19**. If the ink in the ink receiving portion **18b** is less than or equal to the amount of ink that can be held in the ink holding member **19**, most of the ink in the ink receiving portion **18b** is absorbed in the ink holding member **19**. On the other hand, if an amount of ink exceeding the amount of ink that can be held in the ink holding member **19** is present in the ink receiving portion **18b**, the ink is retained in the ink receiving portion **18b** in a state where the ink is not held in the ink holding member **19**. A part of the wall **18a** of the ink receiving portion **18b** has a guiding portion **18c** that is a liquid guiding portion whose height is lower in the **+Z** direction. If the liquid surface of the ink retained in the ink receiving portion **18b** rises to a predetermined height or more, the ink is guided from the guiding portion **18c** to the outside of the ink receiving portion **18b**. The guiding portion **18c** is not limited to the shape having a low height in a part of the wall **18a**, and may be a hole in the wall **18a**, or may be separately provided instead of being in the wall **18a**.

How the ink is guided to the outside of the ink receiving portion **18b** of the ink tank **8C** will be described below with reference to FIG. **11** to FIG. **14**. FIG. **11** is a schematic view of the ink tank **8C** viewed from the **+X** direction. FIG. **12** is a perspective view illustrating an outline of a part including

the ink tank 8 disposed in the housing 200. FIG. 13 is a diagram of the ink tank 8C, taken along a line B-B in FIG. 11, and viewed from the +Y direction. FIG. 14 is a top view of the ink tank 8C, taken along a line C-C in FIG. 11, and viewed from the +Z direction. As described above, the film 20a is welded to the side surface 21c where the guiding portion 18c is provided in the ink tank 8C according to the present embodiment, and the groove defining each of the flow paths 31 and 32 and the film 20a are welded together. Thus, there is a clearance D1 between the side surface 21c and the film 20a. In addition, an upper part of the side surface 21c has a flow path 33 near the guiding portion 18c.

The flow path 33 is formed of an end portion of the film 20a described above, a side surface 21a (the top surface, first surface) of the ink tank 8C, and the wall 18a of the ink receiving portion 18b. The ink guided from the guiding portion 18c flows into the clearance D1 via the flow path 33. In this process, the ink flowing into the clearance D1 runs in the -Z direction by gravity along a side portion 29 of the groove defining each of the flow paths 31 and 32, and moves through an ink channel 320 illustrated in FIG. 11.

Here, a capillary force generated between the side surface 21c of the ink tank 8 and the film 20a acts on the ink passing through the ink channel 320, so that the movement in the -Z direction of the ink is inhibited. If the gravity of the ink flowing into the clearance D1 from the ink receiving portion 18b and the capillary force in the clearance D1 are in a balanced state, the ink is held in the clearance D1 by the capillarity. If the gravity of the ink flowing from the ink receiving portion 18b into the clearance D1 exceeds the capillary force in the clearance D1, the ink further moves in the -Z direction. Here, the ink channel 320 includes a section S1 between a flow path 29b and the flow path 32, and a section S2 between a buffer chamber 29c and the flow path 31. In the sections S1 and S2, the ink channel 320 is surrounded in four directions in the XY directions, and the capillary force acting on the ink is greater than that in the ink channel 320 excluding the sections S1 and S2. The ink moving further in the -Z direction upon passing through the sections S1 and S2 runs along the edge of each of the flow path 29b and the flow path 29a, and is discharged below the ink tank 8C. The ink is discharged from a discharge portion 321 and retained in a retention portion 27 in the housing 200 as illustrated in FIG. 12.

The ink that has arrived at the retention portion 27 can spread and stain the surroundings due to a change in orientation of the recording apparatus 100 or a shock. It is thus desirable to reduce the amount of ink that has arrived at the retention portion 27. For this reason, it is desirable to keep the ink in the clearance D1, i.e., in the middle of the ink channel 320. The capillary force is increased as the clearance D1 is shallower, which makes it easy to retain the ink in the ink channel 320 (holding unit), making it difficult for the ink to arrive at the retention portion 27. The width of the clearance D1 may be appropriately set depending on the dimensions of the ink tank 8C, the viscosity of ink to be used, and the like, but may be set to a value, for example, in the range of about 0.1 mm to 1 mm. In addition, the capillary force of the sections S1 and S2 can be increased with a set smaller width of each of the flow path 29b and the flow path 32 in the +Y direction and a set smaller width of each of the buffer chamber 29c and the flow path 31 in the +Y direction, so that the ink holding force can be enhanced. As with the clearance D1, the width of each of the flow path 29b and the flow path 32 in the +Y direction and the width of each of the buffer chamber 29c and the flow path 31 in the +Y direction

may be appropriately set, but may be set to a value, for example, in the range of about 0.1 mm to 1 mm.

The ink tank 8C according to the present embodiment includes the detection pins 14 on the surface side in the -Y direction (back side) as described above. Similarly, the electric board 15 that connects to the detection pins 14 is on the back side (third side) of the ink tank 8C. It is desirable to have a configuration to prevent the ink from staining a connecting portion (not illustrated) between the detection pins 14 and the electric board 15, and the electric board 15, in order to avoid the occurrence of error in detection by the detection pins 14. In the present embodiment, the guiding portion 18c, the flow path 33, and the ink channel 320 are provided at the side surface 21c, so that a configuration in which the ink passes on a surface different from the back of the ink tank 8 is provided. In addition, the discharge portion 321 is also provided on a surface different from the back of the ink tank 8C, inhibiting the arrival of the ink at a part near the electric board 15. This can reduce the possibility that the ink may stain the connecting portion between the detection pins 14 and the electric board 15 and the electric board 15 itself, and may affect the accuracy of the detection of the ink amount by the detection pins 14. Moreover, the guiding portion 18c, the flow path 33, and the ink channel 320 are provided on the surface that is also different from the front portion 21b of the ink tank 8C, inhibiting the ink from staining the front portion 21b, so that the visibility of the front portion 21b can be well maintained.

The ink channel 320 may not be the channel in which the two paths diverge from the flow path 33 in the Y directions, and may be a channel in which three or more paths diverge, or may be a channel in which two or more paths diverge halfway. A groove portion may be provided in the whole or a part of the ink channel 320 so that the ink channel 320 is surrounded by the groove portion and the film 20a in four directions in the XY directions to hold the ink.

Further, an absorbent material may be disposed in the middle of the ink channel 320 so that the ink is held in the absorbent material. For example, the absorbent material may be bonded to the side surface 21c of the ink tank 8C in the middle of the ink channel 320, or may be in contact with the side surface 21c.

The above-described configuration makes it possible to retain the ink running down near the needle 22 in the ink receiving portion 18b and the ink channel 320, inhibiting leakage of the ink to the outside of the ink tank 8. Thus, ink can be inhibited from staining the inside of the recording apparatus 100 and leakage of ink to the outside of the recording apparatus 100.

A second embodiment will be described below. The description of a configuration similar to the configuration of the first embodiment will be omitted. FIGS. 15A and 15B are external views of an ink tank (an ink tank 8C) according to the present embodiment. FIG. 15A is a perspective view of the ink tank 8C, and FIG. 15B is a top view of the ink tank 8C viewed from the +Z direction. In the present embodiment, an ink flow path 1501 is disposed on a side surface where a guiding portion 18c of the ink tank 8C is disposed. The ink flow path 1501 is formed of a resin similar to a resin of the ink tank 8C, and is a hollow flow path in a shape protruding from the side surface of the ink tank 8C. Ink guided to the outside of an ink receiving portion 18b via the guiding portion 18c moves in a flow path 34 as with the first embodiment, and flows into the ink flow path 1501. A capillary force acts on the ink flowing into the ink flow path 1501, inhibiting movement of the ink in the -Z direction in the ink flow path 1501. If the gravity of the ink in the ink

flow path **1501** and the capillary force are in a balanced state, the ink is held in the ink flow path **1501** by the capillarity. If the gravity acting on the ink in the ink flow path **1501** exceeds the capillary force in the ink flow path **1501**, the ink further moves in the $-Z$ direction, and is discharged from a discharge portion **1502** to the outside of the ink flow path **1501**.

In the ink tank **8C** according to the present embodiment, as with the first embodiment, a film **20a** is welded to a side surface **21c** where a flow path **29a** is provided. Here, a rib **291**, which is a weld surface between the flow path **29a** and the film **20a**, is formed protruding from the side surface **21c**.

The ink discharged from the discharge portion **1502** moves with gravity in the $-Z$ direction as with an ink channel **320**, and upon arriving at the upper side of the rib **291**, the ink moves in a direction indicated by an arrow illustrated in FIG. **15A**, along the rib **291**. Further, upon arriving at an end portion of the rib **291** in the $+Y$ direction, the ink flows into a retention portion **27** of a housing **200** and retained therein.

FIG. **16** is an enlarged sectional view of a part including the ink flow path **1501** of the ink tank **8C** according to the present embodiment, taken along a line D-D in FIG. **15B**. The ink flow path **1501** is configured to turn around into the opposite direction in the Z directions at each of turn-around portions **150a** and **150b**. In particular, from the turn-around portion **150a** to the turn-around portion **150b**, the ink in the ink flow path **1501** moves in the $+Z$ direction against the gravity, and thus the ink easily remains at the turn-around portion **150a**. In comparison with a case where the turn-around portions **150a** and **150b** are not provided and the ink linearly moves in the $-Z$ direction, the ink easily remains in the ink flow path **1501**, allowing the amount of ink that has arrived at the retention portion **27** of the housing **200** to be reduced.

FIG. **17** is a top view of a part including the ink tank **8C** disposed in the housing **200**, as viewed in the $+Z$ direction. In the present embodiment, an ink absorbing member **170** is disposed in the retention portion **27** of the housing **200**. The ink absorbing member **170** lies below the ink tank **8C**, and extends from immediately below the ink tank **8C** in the $+X$ direction. The ink flowing into the retention portion **27** is thereby absorbed and held in the ink absorbing member **170**, further inhibiting ink from staining the inside of a recording apparatus **100** and ink leakage to the outside of the recording apparatus **100**.

It is desirable to set a smaller XY cross-section area of the ink flow path **1501**, in order to enhance the capacity of holding ink by the capillarity. The size of the cross-section area may be appropriately set depending on the dimensions of the ink tank **8C**, the viscosity of ink to be used, and the like, but can be set to a value, for example, in the range of about 0.1 mm^2 to 2.0 mm^2 . In addition, it is desirable that the ink flow path **1501** is longer, in order to increase the amount of ink that can be held in the ink flow path **1501**. The ink flow path **1501** is not limited to the shape in which the two paths diverge from the flow path **33** in the Y directions, and three or more paths may diverge to guide the ink in the $-Z$ direction. Further, the groove portion of the ink flow path **1501** may have a shape to guide the ink linearly from top to bottom in the $-Z$ direction.

In each of the embodiments, instead of the configuration in which the ink introduced into the ink channel can arrive at the retention portion of the housing **200**, a configuration may be used in which the ink can be held using the amount of ink that can be stored in the ink channel **320** as an upper limit without the discharge portion provided in the ink

channel. In this case, a larger amount of ink held in the ink channel further inhibits the ink from staining the inside of the recording apparatus **100** and the ink leakage to the outside of the recording apparatus **100**. Thus, it is desirable to set a longer length as the total length of the ink channel.

According to the embodiments of the present disclosure, leakage of liquid to the outside of a liquid storage container can be inhibited.

While the present disclosure has been described with reference to embodiments, it is to be understood that the disclosure is not limited to the disclosed embodiments. The scope of the following claims is to be accorded the broadest interpretation so as to encompass all such modifications and equivalent structures and functions.

This application claims the benefit of priority from Japanese Patent Application No. 2022-158160, filed Sep. 30, 2022, which is hereby incorporated by reference herein in its entirety.

What is claimed is:

1. A liquid storage container comprising:
a storage portion configured to store liquid;
an opening portion provided on a first surface and configured to allow injection of the liquid into the storage portion;
a liquid receiving portion consisting of the first surface and a wall disposed around the opening portion on the first surface; and
a liquid holding unit configured to hold the liquid guided by a guiding portion from the liquid receiving portion to outside of the liquid receiving portion,
wherein the liquid holding unit includes a second surface different from the first surface of the liquid storage container and a flexible member, and
wherein a part of the liquid is held in a clearance between the second surface and the flexible member, when the liquid is guided by the guiding portion.
2. The liquid storage container according to claim 1, wherein the liquid holding unit is a hollow body on the second surface different from the first surface of the liquid storage container.
3. The liquid storage container according to claim 1, wherein an electric board is on a third surface different from both the first surface and the second surface of the liquid storage container.
4. The liquid storage container according to claim 3, wherein the liquid holding unit includes a discharge portion configured to discharge at least a part of the liquid to outside of the holding unit.
5. The liquid storage container according to claim 4, wherein the liquid discharge portion discharges the liquid in a direction different from the third surface.
6. The liquid storage container according to claim 4, wherein the liquid storage container is disposed in a housing of the liquid ejection apparatus, and a retention portion is disposed in the housing and below the discharge portion.
7. The liquid storage container according to claim 3, further comprising a detection unit configured to detect an amount of the liquid stored in the liquid storage container, wherein the electric board connects to the detection unit.
8. The liquid storage container according to claim 1, further comprising a liquid holding member in the receiving portion.
9. A liquid ejection apparatus comprising the liquid storage container according to claim 1.
10. The liquid ejection apparatus according to claim 9, further comprising a liquid ejection head configured to form an image by ejecting ink as the liquid to a medium.

11

11. The liquid container according to claim 1, wherein the flexible member is welded to the second surface to form the clearance.

12. A liquid storage container comprising:
 a storage portion configured to store liquid;
 an opening portion provided on a first surface, and con-
 figured to allow injection of the liquid into the storage
 portion;
 a liquid receiving portion consisting of the first surface
 and a wall disposed around the opening portion on the
 first surface; and
 a liquid holding unit configured to hold the liquid guided
 by a guiding portion from the liquid receiving portion
 to outside of the liquid receiving portion,
 wherein the holding unit is a hollow body on a second
 surface different from the first surface of the liquid
 storage container, and
 wherein the hollow body comprises a turn-around portion
 for turning around into an opposite direction in a Z
 direction.

13. The liquid storage container according to claim 12,
 wherein the liquid holding unit includes a discharge portion
 configured to discharge at least a part of the liquid to outside
 of the holding unit.

12

14. The liquid storage container according to claim 13,
 wherein the discharge portion discharges the liquid in a
 direction different from the third surface.

15. The liquid storage container according to claim 13,
 wherein the liquid storage container is disposed in a housing
 of the liquid ejection apparatus, and a retention portion is
 disposed in the housing and below the discharge portion.

16. The liquid storage container according to claim 12,
 wherein an electric board is on a third surface different from
 both the first surface and the second surface of the liquid
 storage container.

17. The liquid storage container according to claim 16,
 further comprising a detection unit configured to detect an
 amount of the liquid stored in the liquid storage container,
 wherein the electric board connects to the detection unit.

18. A liquid ejection apparatus comprising the liquid
 storage container according to claim 12.

19. The liquid ejection apparatus according to claim 18,
 further comprising a liquid ejection head configured to form
 an image by ejecting ink as the liquid to a medium.
